by *Frank E. Wolcott*
Attorney.

UNITED STATES PATENT OFFICE

FRANK E. WOLCOTT, OF WEST HARTFORD, CONNECTICUT, ASSIGNOR, BY MESNE ASSIGNMENTS, TO THE BEARDSLEY & WOLCOTT MFG. CO., A CORPORATION OF CONNECTICUT

ROLL

Application filed May 23, 1927. Serial No. 193,637.

My invention relates to rolls.

It has for its object to provide an improved roll, and more particularly an improved roll adapted to use as a rubbing or sharpening roll or the like. A still further object is to provide an improved roll especially adapted to use in connection with a stopper for safety razor blades wherein the sharpening member is connected in an improved manner to the roll and the roll construction is improved and simplified in such manner as substantially to reduce the cost of the same. These and other objects and advantages of my improved construction will, however, hereinafter more fully appear.

In the accompanying drawings I have shown one embodiment which my invention may assume in practice, the same being illustrated in connection with a stopper roll, although it will be understood that the invention is not limited to embodiment in such a roll.

In these drawings,—

Figure 1 is a side elevation of a roll equipped with my improvement, showing the spiral sharpening strip in position at one end and withdrawn at the other to show the aperture;

Fig. 2 is a side elevation of the roll when turned 90°, one end of the same being shown in vertical section to facilitate illustration of the sharpening strip and pin connection;

Fig. 3 is an end view of one end of the roll, the sharpening strip being omitted to show its end slot and the roll bore;

Fig. 4 is an end view of the roll with the sharpening strip thereon in position in its end slot and ready to receive the pin, and

Fig. 5 is a similar end view after the pin has been inserted but showing the pin in section.

In this illustrative construction I have shown a roll 1 having a spiral sharpening member 2 thereon and herein disposed in a shallow narrow spiral groove 3, the member 2 preferably being formed of leather or other suitable material adapted to engage and sharpen the edge of a blade when the roll is rotated in contact therewith, and the roll herein being equipped with improved means

for connecting the ends of this member 2 to the roll as hereinafter more specifically described.

It being understood that the connection at each end of the roll is of the same construction, a specific description of the right hand end of Figs. 1 and 2 is believed to be sufficient. Here it will be noted that the spiral groove 3 passes spirally across a communicating radial slot 4 formed in the right hand end of the roll, which in turn communicates with a short longitudinal slot 5 within the roll and with the roll bore 6, the slot 5 and bore 6 being parallel to one another and communicating as shown. More particularly, it will be noted that the slot 4 is relieved to facilitate the entry of the end of the strip. For example, the corners 7 and 8 of the slot 4 are preferably rounded slightly and the vertical edges 9 of the slot are also slightly rounded or beveled, as shown, as is also the edge 10; while the edges or walls 11 are caused to diverge slightly. Thus it will be noted that when the strip 2 is brought around in the groove 3, the end of this strip, when of suitable length, may be bent near its extremity and forced laterally into the slot 4 in such manner that, while lying flat in the slot it extends through the same opposite the slot 5 and the end of the bore 6 and lies transversely of the latter, the special shaping of the slot, its corners 7 and 8, and its edges 9 serving to facilitate its insertion. In this position, illustrated in Fig. 4, it will be noted that the end of the strip is definitely positioned due to its inter-engagement with the roll, including the spiral groove and the end slot.

Cooperating with my improved means above described, I have also provided other improved attaching means in the form of a pin, generally indicated at 12. Herein, this pin forms the spindle for the roll and is inserted in the bore by driving the same into the latter when the sharpening strip is in the position illustrated in Fig. 4. Here it will also be noted that to facilitate driving in of this pin the inner end of the same is made rounded and smooth and of slightly reduced cross section, as shown at 13. Further, to pre-

vent rotation between the pin and roll and to hold the end of the sharpening strip securely while facilitating driving, the pin is also preferably roughened, herein longitudinally fluted, between its ends, as shown at 14, this portion being of slightly greater diameter than the bore. Also, to limit the inward movement of the pin and enable the outer end thereof to form a journal, a smooth annular head 15 is provided on the outer end of the pin, this head 15 being of slightly greater diameter than the portion 14. It will also be noted that in this construction the pin is adapted to extend approximately to the inner end of the bore 6, though, as shown, preferably not contacting with the inner end of the same. Thus, it will be observed that when the pin is driven in, the end of the strip 3, which as shown in Fig. 4 extends across the bore 6 and is of the same uniform strong cross section as the rest of the strip, is forced inward in such manner as to displace the end of the strip laterally and make it occupy the position in the longitudinal inner groove 5 illustrated in Fig. 2, wherein it is securely clamped by the pin, the fluted surface of the pin acting not only to hold the pin securely in position, but also to hold the strip.

In the use of my improvement it is found that it is possible to utilize pins 12 of identic construction, not only to attach the opposite ends of the sharpening strip and also to form the spindle or studs on which the roll is journaled in the stropper frame, but also to connect the roll gear 16 to the driven end of the roll. To do this, the gear 16, which is provided with an axial opening registering with the bore 6 at that end, is simply placed coaxially with the bore after the sharpener strip has been inserted in the slot, as shown in Fig. 4, and the pin is then driven through the gear until its portion 15 abuts against the outer surface of the gear, the fluted portion 14 of the pin then also acting to prevent rotation of the gear while the end of the strip 3 is engaged by this fluted portion and the strip is also clamped between the gear and the roll. In this end of the roll the pin 12 thus performs another function, i. e. that of holding the gear in place, in addition to the function of holding the sharpener strip in position and forming a spindle for the roll.

As a result of my improved construction, it is found possible to hold the leather strip securely in the desired position and also to fix the pins securely in position in the roll, the roughened area on the pins acting effectually to engage both the end of the strip and the bore in such manner as to prevent turning. As a result of this construction, it is also possible to use a roll formed of softer material than the pin and thus enable the flutes on the pin not only to be embedded in the end of the strip in such manner as to prevent rotation, but also to be embedded in the

surface of the bore. My improved construction of the roll body is also such as, while providing for this secure fastening, to make it possible to produce the roll body by casting, as distinguished from machining, and thereby enable the cost thereof to be kept very low. Further, it is possible substantially to reduce the cost of the rolls considered as a finished whole, not only as regards cost of material, but as regards assembly, while at the same time producing a construction which can be very quickly and simply assembled. These and other advantages of my improved construction will, however, be clearly apparent to those skilled in the art.

While I have in this application specifically described one form which my invention may assume in practice, it will be understood that the invention may be modified and embodied in various other forms without departing from its spirit or the scope of the appended claims.

What I claim as new and desire to secure by Letters Patent is:—

1. A spirally grooved razor stropper roll having an axial bore therein and a radial slot in its end communicating with said groove and bore and having a spiral stropper member disposed in the spiral groove therein and a bent end on said member lying in said slot and projecting into said bore and adapted to be deflected therein by a spindle inserted therein.

2. In combination, a razor stropper roll having an axial bore therein and an end slot communicating therewith and extending radially transversely across one-half of the end of said roll, a stropper member wound spirally on said roll and having an end in said end slot and extending into said bore, a spindle disposed in said bore and engaging therein the end of said stropper member in said bore.

3. In combination, a roll having a bore and a slot in one end thereof communicating with said bore, a member wound spirally of said roll and having a bent end in said slot, and extending into said bore, and a pin adapted to be driven into said bore to deflect the bent end of said member.

4. In combination, a spirally grooved razor stropper roll having a bore and a radial slot in one end thereof communicating with said groove and bore and a longitudinal slot in said bore communicating with said radial slot, a member in said groove having a bent end in said slot and extending into the bore, and a spindle in said bore deflecting the end of said member extending into the bore into said longitudinal slot as said spindle is inserted into said bore.

5. In a razor stropper roll, a gear coaxial with said roll, said roll and gear having registering axial openings therein, a stropper member wound spirally on said roll and hav-

ing a bent end extending into the axial opening therein, and a spindle adapted to be driven through said openings for engaging said roll and gear and the end of said strop-
per member and holding the parts together.

5 6. In combination, a roll having a spiral strip thereon and provided with an end slot and axial bore and a chamber connecting said slot and bore, and a pin insertable in said bore and deflecting in said chamber the end of said strip and having a roughened area engageable with the walls of said bore and the end of said strip.

10 7. In combination, a spirally grooved roll having an axial bore and provided with a communicating opening at its end and an end slot leading to said opening and bore, a member in said groove having an end in said end slot and extending across said opening into said bore, and a spindle insertable in said bore having a driving end adapted to deflect the end of said member, an intermediate portion gripping said bore and member, and an outer end forming a journal for the roll.

15 20 25 In testimony whereof I affix my signature.
FRANK E. WOLCOTT.
